US00D618813S

(12) **United States Design Patent**
Doo

(10) **Patent No.:** US D618,813 S
(45) **Date of Patent:** ** Jun. 29, 2010

(54) **BODY SCULPTING DEVICE**

(75) Inventor: **Hong-Jik Doo**, Seoul (KR)

(73) Assignee: **Dwzone Medical Co., Ltd.**, Seoul (KR)

(**) Term: **14 Years**

(21) Appl. No.: **29/324,156**

(22) Filed: **Sep. 8, 2008**

(30) **Foreign Application Priority Data**

Apr. 2, 2008 (KR) 30-2008-0014045

(51) **LOC (9) Cl.** 28-03

(52) **U.S. Cl.** D24/200

(58) **Field of Classification Search** D24/215, D24/107, 133, 144, 187, 200, 209, 231; 601/1, 601/2, 15, 20, 101, 143; 606/1, 9; 607/2, 607/3

See application file for complete search history.
